UNITED STATES PATENT OFFICE

105,953

DESIGN FOR AN ILLUMINATING DEVICE

Russell L. Hohl, New York, N. Y.

Application August 1, 1936, Serial No. 64,189

Term of patent 14 years

To all whom it may concern:

Be it known that I, Russell L. Hohl, a citizen of the United States and a resident of the city, county, and State of New York, have invented a new, original, and ornamental Design for an Illuminating Device, of which the following is a specification, reference being had to the accompanying drawing, forming part thereof.

In the drawing:—

Fig. 1 is a front elevation of an illuminating device, showing my new design;

Fig. 2 is a top plan view;

Fig. 3 is a side elevation; and

Fig. 4 is a section on the line 4—4 of Fig. 1, with parts shown in elevation.

The dominant feature of my design is the elongated tubular bulb having a plurality of cup-shaped reflectors distributed along it.

I claim:—

The ornamental design for an illuminating device, substantially as shown and described.

RUSSELL L. HOHL.
